DIRECT CURRENT OR LOW FREQUENCY TRANSISTOR AMPLIFIERS HAVING A HIGH INPUT IMPEDANCE

John Dennis Raiphs, Crowborough, England, assignor to National Research Development Corporation, London, England

Filed Mar. 2, 1961, Ser. No. 92,826

Claims priority, application Great Britain Mar. 15, 1960
10 Claims. (Cl. 330—10)

The present invention relates to transistor amplifiers. In former direct current or low frequency transistor amplifiers the only ways in which a high input impedance could be achieved were by either high base and collector feed resistors or an appreciable amount of direct current negative feedback. In either case the maximum input impedance which could be achieved was very limited by temperature effects. It is an object of the present invention to provide a direct current or low frequency amplifier having a high input impedance but in which temperature drift effects, instability and non-linearity are substantially absent.

According to the present invention there is provided a transistor amplifier including a first transistor, an input connected to the base electrode of the first transistor, a resistance-capacity smoothing circuit connected to the emitter electrode of the first transistor, means for impressing voltage pulses on the first transistor to urge it to conduct and amplifying and detecting means operated by the pulse current through the first transistor to charge the smoothing circuit in a sense to cut off the first transistor.

An embodiment of the invention will now be described by way of example and with reference to the accompanying drawings, in which FIGURE 1 and FIGURE 2 are both circuit diagrams of transistor amplifiers.

In FIGURE 1 a source E of a signal voltage having a source resistance R_s is shown applied between terminal A_1 and A_2 , the negative lead from the source being connected to the terminal A_1 and the positive lead from the source being connected to the terminal A_2 . The terminal A_1 is connected to the base electrode of a transistor Q_1 , whose emitter electrode is connected to an output terminal A_3 via the secondary winding of a transformer T_1 and whose collector electrode is connected to a negative voltage line via the primary winding of a transformer T_2 . The base electrode of the transistor Q_1 is connected to the output terminal A_3 via a capacitor C_1 . The terminal A_2 is connected to a positive voltage line, to which the output terminal A_4 is also connected. A resistor R_e and a capacitor C_e are connected in parallel between the terminal A_3 and the terminal A_4 , thus forming a resistance-capacity smoothing circuit. A capacitor C_2 is connected across the primary winding of the transformer T_2 , and a transistor Q_2 has its collector electrode connected to the negative voltage line, its emitter electrode connected to the output terminal A_3 and its base electrode connected to the positive voltage line via the secondary winding of the transformer T_2 .

In operation the output voltage V across the terminals A_3 and A_4 follows the signal voltage E of the source E , although it is higher by a substantially constant small voltage; the output impedance, however, is much lower than the input impedance. The operation is as follows. A source of short positive pulses at a medium repetition frequency (for example, 1 volt for 5 micro-seconds at 3 kc./s.) applies these pulses between the emitter and the base of the transistor Q_1 via the transformer T_1 the capacitor C_1 acting as a low-impedance path to these pulses. The resulting collector current pulse is applied to the primary winding of the transformer T_2 . The

2

voltage output from the secondary winding of the transformer T_2 is applied to the base of the transistor Q_2 and the emitter current of the transistor Q_2 is drawn through the resistor R_e and the capacitor C_e in parallel. The pulses of emitter current are smoothed by the capacitor C_e to give a substantially steady D.C. voltage across the resistor R_e . This resulting voltage V is applied as a bias to the emitter circuit of the transistor Q_1 .

If the voltage V is much greater in magnitude than the voltage E , the transistor Q_1 will be cut off, no waveform will appear across the primary winding of the transformer T_2 and the transistor Q_2 will therefore be cut off also. Thus the voltage V will decay towards zero with a time constant $R_e C_e$. As the voltage V approaches the voltage E the positive peak of the emitter pulse will cause the transistor Q_1 to conduct, causing a much larger positive voltage pulse on the collector of the transistor Q_1 and a corresponding negative voltage pulse on the base of the transistor Q_2 . If this pulse is smaller in amplitude than the voltage V then the transistor Q_2 will not conduct, and, the emitter current pulses of the transistor Q_1 being relatively small the voltage V will continue to decay. The current pulses through the transistor Q_1 will increase until the transistor Q_2 conducts on the peaks of the pulses. The pulses in the emitter circuit of the transistor Q_2 will then tend to recharge the capacitor C_e and a stable state will be reached when the peak amplitude in the base circuit of the transistor Q_2 is such that the pulses in its emitter circuit just restore the charge lost on the capacitor C_e between pulses.

The above operation of the circuit ignores the action of the capacitor C_2 which causes the transformer T_2 to operate as a high-Q tuned circuit. The waveform in this case at the collector of the transistor Q_1 is a damped sinusoidal or ringing waveform, whereby the need for D.C. restoration at the base of the transistor Q_2 is eliminated and, since the transistor Q_2 may conduct on two or three successive peaks of the waveform, the peak emitter current required is reduced.

Since the peak voltage of the voltage waveform on the base electrode of the transistor Q_2 is equal to V , this waveform may be separately amplified and detected with a peak detector, enabling direct current amplification to be achieved with a change of reference voltage or the polarity changed, or both, and thus with the elimination of the constant input to output voltage difference mentioned above.

The preferred mark-space ratio of the positive pulses applied to the emitter electrode of the transistor Q_1 , that is to say, the preferred ratio between the pulse width and the time elapsed between the pulses is the ratio between the maximum signal input current of the amplifier and the peak allowable emitter electrode current for the transistor Q_2 divided by the total A.C. gain between the two electrodes. Instead of positive pulses applied to the emitter electrode of the transistor Q_1 , negative pulses may be applied to its base electrode: these have the same effect on the collector electrode current.

FIGURE 2 is a further circuit diagram of a modified form of the transistor amplifier shown in FIGURE 1. Components in FIGURE 2 having a similar function as components in FIGURE 1 are marked with the same reference.

FIGURE 2 shows two input terminals A_1 and A_2 , the terminal A_1 being connected to the base of a transistor Q_1 . The collector of the transistor Q_1 is connected to a primary winding of a transformer T_2 across which a capacitor C_3 is connected. The output from a secondary winding of the transformer T_2 is applied to an emitter follower transistor Q_3 , the emitter of which is connected to the base of a transistor Q_2 . The emitter of the

transistor Q_2 is connected to a smoothing circuit R_e , C_e , C_4 and to the emitter of the transistor Q_1 through a secondary winding of a transformer T_1 and a stopper resistor R_1 . The secondary winding of the transformer T_1 is connected between the base and emitter of the transistor Q_1 via a capacitor C_1 and the resistor R_1 . In the case of the circuit of FIGURE 2, the pulses applied between the emitter and base of the transistor Q_1 are derived from a conventional free-running blocking oscillator comprising a transistor Q_5 , resistors R_2 and R_3 , a capacitor C_3 and primary and tertiary windings of the transformer T_1 , as shown in the drawing. This blocking oscillator has a pulse recurrence frequency of 3 kc./s. and provides pulses of approximately 4 to 5 microseconds wide, the actual width being adjustable by the resistor R_2 to obtain optimum operation of the circuit. This optimum occurs when the pulse width is equal to the half period of oscillation of the tuned circuit formed by the primary winding of the transformer T_2 and the capacitor C_2 . Alternatively, the pulse width may be fixed and the value of the capacitor C_2 or the inductance of the primary winding of the transformer T_2 adjusted to achieve the same optimum operation of the circuit.

The output of the amplifier shown in FIGURE 2 is derived from a tertiary winding of the transformer T_2 through a transistor peak detector circuit comprising a transistor Q_4 and a smoothing circuit C_5 , R_7 . The base of the transistor Q_4 is connected to the tertiary winding of the transformer T_2 and its emitter is connected to the smoothing circuit C_5 , R_7 . An output is taken from the transistor peak detector from across the smoothing circuit C_5 , R_7 via output terminals A_3 and A_4 .

The operation of the circuit shown in FIGURE 2 is similar to that shown in FIGURE 1. The emitter follower transistor Q_3 is, in this case, inserted between the secondary winding of the transformer T_2 and the base of the transistor Q_2 to provide increased current gain.

The action of the peak detector transistor Q_4 may be seen from the following description. The transistor Q_2 is a form of emitter follower with the exception that it has a long time-constant R_e , C_e , C_4 in its emitter circuit. It follows that the peak voltage on its base is substantially equal to the voltage on its emitter. Also from the description given in relation to FIGURE 1, the voltage on the emitter of the transistor Q_2 will be seen to be very nearly equal to the input voltage across the input terminals A_1 and A_2 . Therefore, the peak voltage on the base of the transistor Q_2 is very nearly equal to the input voltage. The transistor Q_3 is also an emitter follower and the peak voltage on its base will be very nearly equal to the peak voltage on its emitter, which is connected to the base of the transistor Q_1 . Therefore, the peak voltage on the base of the transistor Q_3 will be very nearly equal to the input voltage. The voltage on the base of the transistor Q_3 will be stepped up by the turns ratio between the tertiary and secondary windings of the transformer T_2 and applied to the peak detector transistor Q_4 . It necessarily follows that the output of the peak detector transistor Q_4 is proportional to the input voltage.

The circuit shown in FIGURE 2 may be such that the amplifier has an overall voltage gain of 1.5 and has a low impedance output, this output being transposed to the +6 volt line shown in the drawing. The input impedance is greater than 15 megohms and the maximum output is approximately six volts.

For optimum efficiency the ringing frequency of the transformer T_2 should be such that a half period is equal to the input pulse width. This is achieved by varying the pulse width by means of a variable (preset) resistance R_2 in series with the base electrode of the transistor Q_5 . Otherwise the operation of the circuit is the same as that of the circuit in FIGURE 1.

The preferred component values of the circuit described with reference to FIGURE 2 are as follows:

Transistor Q_1	OC202
Transistor Q_2	TK40A
Transistor Q_3	TK40A
Transistor Q_4	TK40A
Transistor Q_5	TK40A
Resistor R_e	3.3K Ω
Resistor R_1	1000
Resistor R_2	1K Ω
Resistor R_3	470K Ω
Resistor R_4	10K Ω
Resistor R_5	4.7K Ω
Resistor R_6	3900
Resistor R_7	47K Ω
Capacitor C_e	μ F 4
Capacitor C_1	μ F 0.1
Capacitor C_2	pF 500
Capacitor C_3	pF 2000
Capacitor C_4	μ F 0.01
Capacitor C_5	μ F 0.1

The resistor R_6 may be adjusted if necessary to give optimum linearity at low signal voltages.

The effective capacitative load on the emitter of the transistor Q_3 may cause the input impedance across its base to contain a negative resistance so that the circuit oscillates; this may be overcome by deliberately damping the transformer T_2 .

Those skilled in the art will realize that the invention has many possible applications, for example, with a condenser input coupling and a base bias applied to the transistor Q_1 through a high resistance the circuit may be used as a low frequency amplifier; the high input impedance and the facility of transposing the output make it a possible replacement for a thermionic valve cathode follower following piezo-electric pressure transducers and similar devices; and the facility of reversing the polarity of the output or producing outputs of both polarities may be used in, for example, analogue computers.

I claim:

1. A transistor amplifier including a first transistor, a resistance-capacitance smoothing circuit connected to the emitter of said first transistor, means for connecting an input voltage between the base of the transistor and to the side of said smoothing circuit remote from the emitter, means for applying voltage pulses between the base and emitter of said first transistor in a sense tending to increase the conduction thereof, and amplifying and detecting means connected between the collector of the said transistor and the said smoothing means so as to be operated by the pulse current through the said transistor to charge the smoothing circuit in a sense tending to reduce the conduction through the said transistor.

2. A transistor amplifier as set forth in claim 1 wherein said means for applying voltage pulses between the base and the emitter of said first transistor includes the secondary winding of a transformer, the said secondary winding being connected between the said emitter and the said smoothing circuit.

3. A transistor amplifier as set forth in claim 2 further comprising a free-running blocking oscillator the output of which is connected to the primary winding of the said transformer.

4. A transistor amplifier as set forth in claim 1 wherein the amplifying and detecting means includes a transformer the primary winding of which is connected to the collector of the said first transistor, and a second transistor having its base connected to the secondary winding of the said transformer and its emitter connected to the said smoothing circuit.

5. A transistor amplifier as set forth in claim 4 wherein a capacitor is connected across the primary winding of the said transformer to form a tuned circuit therewith.

6. A transistor amplifier as set forth in claim 1 wherein

the amplifying and detecting means includes a transformer the primary winding of which is connected to the collector of the said first transistor, a second transistor having its base connected to the secondary winding of the said transformer and a third transistor having its base connected to the emitter of the said second transistor and its emitter connected to the said smoothing circuit. 5

7. A transistor amplifier as set forth in claim 6 further comprising a tertiary winding on the said transformer and a transistor peak voltage detector connected to the output 10 of the said tertiary winding.

8. A transistor amplifier including

- (a) a first transistor,
- (b) a smoothing circuit,
- (c) a first transformer having its secondary winding 15 connected between the emitter of the first transistor and the smoothing circuit,
- (d) means for applying an input signal between the base of the said first transistor and the side of the smoothing circuit remote from the said secondary winding, 20
- (e) a second transistor having its emitter connected to the junction of the said secondary winding and the said smoothing circuit,
- (f) a capacitor connecting the said junction to the base 25 of the first transistor and
- (g) a second transformer having its primary winding connected to the collector of the said first transistor and its secondary winding connected to the base of the said second transistor.

9. A transistor amplifier including
- (a) a first transistor,
  - (b) a smoothing circuit,
  - (c) a first transformer having its secondary winding connected between the emitter of the first transistor and the smoothing circuit,
  - (d) means for applying an input signal between the base of the first transistor and the side of the smoothing circuit remote from the said secondary winding,
  - (e) a second transistor having its emitter connected to the junction of the said secondary winding and the said smoothing circuit,
  - (f) a capacitor connecting the said junction to the base of the said first transistor,
  - (g) a third transistor having its emitter connected to the base of the said second transistor and
  - (h) a second transformer having its primary winding connected to the collector of the said first transistor and its secondary winding connected to the base of the said third transistor.

10. A transistor amplifier as set forth in claim 9 further comprising a tertiary winding on the said second transformer and a transistor peak voltage detector connected to the output of the said tertiary winding.
